[57] CLAIM

The ornamental design for a tobacco package dispenser, as shown and described.

DESCRIPTION

FIG. 1 is a front elevational view of a tobacco package dispenser showing my new design;

FIG. 2 is a top plan view thereof;

FIG. 3 is a left side elevational view thereof, the right side being a mirror image of that shown;

FIG. 4 is a rear elevational view thereof;

FIG. 5 is a bottom plan view thereof; and,

FIG. 6 is a top, front, and left side perspective view thereof.

FIG. 1

*FIG. 2**FIG. 3**FIG. 4**FIG. 5**FIG. 6*
